UNITED STATES PATENT OFFICE.

FRED EVANS, OF NEW YORK, N. Y., ASSIGNOR TO HENRY E. STEVENS, JR., OF NEW YORK, N. Y.

SEALING-TAG.

1,313,888.

Specification of Letters Patent. Patented Aug. 26, 1919.

Application filed July 22, 1915. Serial No. 41,351.

To all whom it may concern:

Be it known that I, FRED EVANS, residing at New York, in the county of New York and State of New York, have invented certain new and useful Improvements in Sealing-Tags, of which the following is a specification.

This invention relates to an improvement in shipping tags or the like, and particularly to one which may be described as a "sealing" or "self-sealing" tag, and the principal object sought to be attained by the invention is to provide a simple, cheap, but efficient means whereby the tag may be quickly and effectively sealed to any desired object.

A further object is to provide a reinforcing device for the tag and to provide sealing means in said reinforcing device.

20 A further object is to provide a reinforcing device so shaped and constructed that it may be stamped or cut from a blank of material in such a way as to leave practically no waste whatever.

25 A further object is to arrange the parts so that portions of the reinforcing device, which are employed in shaping the sealing part thereof, incidentally serve as an auxiliary means for attaching the reinforcing device to the material of the tag.

Other objects and aims of the invention, more or less specific than those referred to above, will be in part obvious and in part pointed out in the course of the following

35 description of the elements, combinations, arrangements of parts and applications of principles, constituting the invention; and the scope of protection contemplated will be indicated in the appended claim.

40 In the accompanying drawings which are to be taken as a part of this specification, and in which I have shown a merely preferred form of embodiment of the invention:

Figure 1 is a view of a portion of a shipping tag illustrating the invention applied thereto.

Fig. 2 is a view similar to that shown in Fig. 1, but being taken from the opposite side of the tag.

50 Fig. 3 is an enlarged sectional view taken substantially upon the plane of line III-III of Fig. 2.

Fig. 4 is a view similar to that shown in

Fig. 3, but being taken upon the plane of line IV-IV of Fig. 2, showing the reinforcing device attached to the material of the tag but prior to the bending over of the attaching means.

Fig. 5 is a view similar to that shown in Fig. 4, but the attaching means being here shown bent into attaching position.

Fig. 6 is a plan view of a section of material illustrating the manner of stamping or cutting out the parts of the reinforcing member therefrom.

Fig. 7 is a plan view of the reinforcing device indicating the slits formed therein for providing the retaining and sealing means.

Fig. 8 is a view similar to that shown in Fig. 1 but showing the reinforcing device to be formed from parts of the blank shaped in the blank incident to the cutting therefrom of the reinforcing devices shown in Fig. 1; and

Fig. 9 is a view similar to that shown in Fig. 8, but illustrating the opposite side of the tag.

Fig. 10 represents a modification.

Referring to the drawings for a detailed description of the structure illustrated, the reference character L indicates the shipping tag. This is of the ordinary, or preferred, formation and comprises usually a rectangular sheet of tough, flexible cardboard, usually having its upper corners cut away for appearance sake.

The reference character G indicates the reinforcing member or device. This is formed of a circular blank or body of sheet metal, preferably tin, having a series of tangs 1, struck therefrom intermediate the central portion and the periphery thereof, said tangs being preferably spaced equi-distant circumferentially of the blank. There may be as many as desired of these tangs, though four is a desirable number, and each is preferably sharpened at its outer end so as to easily puncture the material of the card in being attached thereto, in the manner seen particularly in Fig. 4.

Each of the tangs is preferably triangular, being severed from the blank or body along two sides only. The remaining side provides a line of connection along which the tang is bent laterally so as to stand in a

position to readily pierce the material of the tag. The unsevered sides 2 of the triangles are arranged relatively nearer to the periphery of the body, and the severed sides 5 converge toward the center, as best indicated in Figs. 1 and 7.

At the central portion of the blank a pair of slits 3 and 4 is provided, said two slits comprising an inverted T-shaped slit.

10 The reinforcing device may be attached to the tag in any approved manner, but one method of procedure is indicated clearly in Figs. 4 and 5.

This method includes forcing the tangs 1 15 through the material of the tag, as shown in Fig. 4, and bending the projected ends back upon the opposite surface of the tag, as shown in Fig. 5. During this operation, or subsequently, the triangular parts 5 formed 20 by the intersection of the slits 3 and 4 are forced through the material of the tag and bent backwardly so as to grip tightly upon the material, as clearly seen in Fig. 5. The line of bend for the parts 5 is clearly indicated by dots in Fig. 7. A considerable portion of the length of the slit 3 is left unbent, except such slight bend as is given thereto 25 incidental to the formation of the slit.

A slit may be provided through the material of the card underlying either or both 30 of the slits 3 and 4, if desired, but usually this is not necessary as the force required to bend over the parts or tangs 5 is ample to cause the same to pierce and tear the material of the tag to a desired extent. This 35 in fact provides a much more substantial grip between the reinforcing device and the tag for the reason that the fibers of the tag provide a cushion at the edges of the tangs and effectually prevent likelihood of the edges cutting through the material of the tag. The material of the tag piled up or 40 pressed under the tangs serves the same purpose.

45 In use the end of the attaching cord is inserted through the opening 6 formed by the bending over of the tangs 5 and the passage of said tangs through the material of the card. It is then moved upwardly along the 50 slit 3, which, being of less width than the diameter of the cord, comprises a friction grip for retaining the cord rigidly against accidental detachment, and positively against longitudinal movement through the 55 slit.

In cases where the material of the card is not provided with a slit underlying the slit 3 of the reinforcing device, the movement 60 of the cord upwardly through the slit is sufficient to tear or cut the material of the card. This incidentally provides a tighter grip for the cord and also forces fibers of the card into the slit, which fibers protect the cord from injury by the edges of the 65 slit.

The sealing means thus provided may be utilized only as a means for retaining a length of cord assembled with the tag, in which instance both ends of the cord would be free and in use could be passed around any desired object and the ends tied together in the usual manner. If desired, however, one end of the cord could be fixed rigidly to the tag, as by being caught between the tag and the reinforcing device. In this instance the free end would be passed around the article, inserted through the opening 6 and drawn up into the slit 3. This will provide a sufficiently effective seal between the tag and the article for all practical purposes.

As above suggested, it is also a part of this invention to cut or stamp out the bodies in such manner that practically all of the material of the blank may be employed. Since 85 the exterior contour of the blank has little to do with the effectiveness of the sealing means, this object is readily accomplished in the manner suggested in Fig. 6. In this figure the circular bodies or blanks leave the 90 hollow-sided squares 7 between them. These squares may be utilized in practically the same manner as pointed out for the circular blanks. In this instance the sharp corners 8 of the squares serve as tangs, as 95 clearly seen in Figs. 8 and 9. Otherwise the structure is the same as shown in the other figures.

As many changes could be made in this construction without departing from the 100 scope of the following claim, it is intended that all matter contained in the above description or shown in the accompanying drawing shall be interpreted as illustrative only and not in a limiting sense.

105 The manner in which the portions 5 grip upon the material of the card is very efficient in withstanding strains. The angular depression of the parts 5 relatively to each other and relatively to the direction of strain 110 imparted to the reinforcing member G by the attaching cord, together with the folded and tightly gripped condition of the material of the card under the parts 5, gives exceptional strength to the connection between the card and the reinforcing member.

115 In the modification Fig. 10, this form of connecting means between the reinforcing member and the tag is depended upon solely. In this modification the turned portions are 120 indicated by the reference numeral 9 and the slit 3 is omitted, though obviously the slit could be provided if desired. With the slit omitted, however, the opening 6 receives the attaching cord loosely therethrough in 125 the ordinary manner.

Having thus described my invention what I claim as new and desire to secure by Letters Patent is:

A reinforcing device for a tag or the like 130

comprising a body of material adapted to rest upon one surface of the tag, the body having a T-shaped slit therein, the triangular portions of the body formed by the intersection of the head and stem portions of the slit being bent to form attaching means for attaching the body to the tag, and a portion of the stem of the slit providing grip-

ping means for holding a cord attached to the tag. 10

In testimony whereof I affix my signature in the presence of two witnesses.

FRED EVANS.
